JET CIRCULATION WASHING MACHINE

Thomas F. Russell, Fergus, Ontario, Canada

Application March 1, 1947, Serial No. 731,785

5 Claims. (Cl. 68—184)

1

This invention relates to washing machines and the object of the invention is to devise a washing machine which will have a minimum of moving parts and which will wash linen quickly and effectively without tearing or damaging the material.

The washing machine art is an old one and many washing machines perform the washing operation by means of a dolly or a reciprocating or rotating tub. In accordance with other constructions the washing operation is performed by circulating washing fluid through the clothes.

The difficulty with the latter type of washing machine has been to obtain thorough circulation and recirculation of the washing fluid through every part of the linen to be cleaned and with this in view various arrangements have been devised and patented.

I have found that satisfactory results can be obtained in a manner which is most simple and effective. Briefly, according to the present invention the jet of washing fluid is injected into the tub at a point adjacent the bottom thereof and at substantially the geometrical centre of the bottom and a deflector plate is mounted in the tub above the point of injection of the washing fluid.

With this arrangement the articles to be cleaned circulate rapidly with the washing fluid, rising at the centre of the tub, striking the deflector plate, passing outwardly towards the side of the tub and then passing downwardly and inwardly to the bottom of the tub, from where they again are carried upwardly by the washing fluid and the process is repeated.

The invention is hereinafter more particularly described and is illustrated by way of example in the accompanying drawings in which:

Figure 1 is a vertical section through the machine on the line 1—1 in Figure 2;

Figure 2 is a horizontal section through the machine;

Figure 3 is a perspective view of the deflector plate;

Figure 4 is a perspective view of a modified form of the deflector plate;

Figure 5 is a vertical section through the machine, showing a modified form thereof;

Figure 6 is a fragmentary section of the machine in Figure 5 showing a modified construction of deflector plate; and

Figure 7 is a fragmentary section of the machine in Figure 5 showing a still further modified construction of deflector plate.

In the drawings corresponding numerals refer to corresponding parts in the different figures.

2

Referring to Figures 1 to 3 inclusive, the tub 1 is cylindrical, but may be rectangular, spherical or spheroidal, and is provided with a top or cover 2 removably mounted thereon.

5 Located substantially at the geometric centre of the bottom of the tub is an opening through which extends a pipe 4, the open end of which forms a jet or nozzle for injecting washing fluid into the tub. The end of this pipe 4 is preferably located at or close to the bottom of the tub, most preferably slightly above the bottom to provide a space between the jet opening and the bottom of the tub. However the pipe may extend as much as half way from the bottom of the tub if sufficient washing fluid is used to provide ample space between the end of the pipe and the deflector plate (hereafter described) to permit free circulation of the washing fluid and the linen in the tub.

10 Surrounding the jet is a perforated screen 5 spaced above the bottom of the tub and extending downwardly into substantial contact at its outer edges with the bottom of the tub. Located in the bottom of the tub adjacent to the pipe 4 and beneath the perforated screen 5 is a drainage opening connected to a drainage pipe 6 which forms a closed circuit with the fluid injecting pipe 4. In this circuit is any suitable type of liquid pump 7 preferably operated by a motor 8. Therefore, there is a continual recirculation of the washing fluid. Another drainage opening (not shown) may be provided for draining off the washing fluid after the completion of the washing operation.

15 A deflector plate 9 is provided, in practice preferably having a diameter of substantially half the diameter of the tub and preferably having its undersurface or part thereof concaved. However, a deflector plate of substantially the same diameter as the inside of the tub will operate satisfactorily, provided there is sufficient space between the edge of the plate and the sides of the tub to permit the plate to float up and down and to relieve the pressure of steam coming off the hot washing fluid.

20 However, if the plate appreciably exceeds in diameter one-half the diameter of the inside of the tub the suction caused by the downward flow of washing fluids at the outside of the tub tends to suck it down below the surface of the washing fluid in the tub and to compress the linen in the tub so as to interfere with the free circulation of the washing fluid and linen. In Figure 3 is shown a plate having its whole undersurface concaved and in Figure 4 is shown the plate having a portion thereof adjacent its centre concaved. The

plate is circular and may be formed of metal or other suitable material.

The deflector plate is adapted to rest on the surface washing fluid above the linen which is being washed, the term linen being used in a generic sense to describe clothes, curtains and other material which may be washed in a washing machine. The flow of the washing fluid will retain the plate at or near the surface. Best results are obtained by the use of considerably more washing fluid than is necessary to cover the linen in the tub.

It is found in practice that if the deflector plate is merely placed on the surface of the washing fluid with its centre substantially vertically above the centre of the ejector pipe 4, it will, if its undersurface is formed as shown in Fig. 4, remain in substantially that position during the washing operation. The action of washing is that the washing fluid ejected from the pipe 4 travels upwardly along the vertical centre line of the wash tub, carrying the linen with it and strikes the deflector plate which directs it together with the linen outwardly and downwardly to the bottom of the tub, where the washing fluid passes to the drainage outlet pipe 6. The perforated screen 5 acts as a guard to prevent the drainage pipe 6 from becoming stopped up by the material in the tub. The linen which is carried downwardly to the bottom of the tub by the washing fluid is sucked into the centre and carried upwardly by the washing fluid which is ejected into the tub by the ejector pipe 4.

Although the deflector 9 will remain in position on the surface of the washing fluid if properly placed in position without any support, it is desirable to provide guide means to prevent accidental displacement of the deflector plate and this is accomplished by securing a rod 10 to the centre of the upper surface of the deflector plate and extending at right angles to the horizontal plane of the plate. A hollow tube 11 is secured to the centre of the cover 2 of the tub and extends downwardly at right angles thereto. The rod 10 and the hollow tube 11 telescope so as to provide a vertically floating mounting for the deflector plate, retaining it in its central location above the jet but permitting it to move up and down on the surface of the washing fluid so that it will always remain on the surface of the washing fluid contained in the tub and yet its position relative to the tub and the top may change depending upon the quantity of washing fluid contained in the tub.

To get the desired circulatory action of the washing fluid, it is necessary that the deflector plate be located on or at the surface of the washing fluid, but within a predetermined low and high point, which can readily be determined in practice, the deflector plate acts efficiently regardless of its height above the bottom of the tub so long as it is resting on the surface of the washing fluid and arranged above the injector pipe with its centre located substantially on the centre line of the injector pipe.

In Figure 5 is shown a spheroidal tub, in which the plate 19 acts as a closure for the tub 21. It is provided with a flange 19^a which extends through the opening in the tub, being spaced from the edges of the opening sufficiently to permit the flange 19^a to slide up and down in the opening and to permit the escape of steam between the walls of the flange and the sides of the opening.

In Figure 6 deflector plate 29 is mounted on

bellows 12 secured to closure 24. The bellows expand to permit the plate to rest on the surface of the washing fluid depending on the liquid level. The bellows 12 are adapted to fold up within a recess formed by a flange 24^a which extends down from the closure 24 spaced from flange 22^a around the opening in the tub 22. The plate 29 when in its uppermost position bears against flange 24^a. A tube 13 extends through flange

10 22^a to permit escape of steam.

In Figure 7 the deflector plate is shown secured to flange 25^a of the closure 25. In this construction the position of the plate 39 is fixed relative to the tub 23 and therefore in order that it may operate the tub must be filled until the surface of the washing fluid reaches the under face of the plate 39.

It will be seen from the above that the objects of this invention have been attained in a very simple and effective manner.

It is thought that the construction and use of the invention will be apparent from the above description of the various parts and their purpose. It is to be understood that the form of my invention herewith shown and described, is to be taken as a preferred example of the same, and that various changes in the shape, size and arrangement of parts may be resorted to, without departing from the spirit of my invention, or the scope of the subjoined claims.

What I claim as my invention is:

1. A machine for washing linen comprising an imperforate tub for holding linen and washing fluid, said tub having a bottom and walls, a filling opening for inserting linen, a drainage opening, a jet opening vertically into the tub at substantially the geometrical centre line and directed along the centre line to inject washing fluid into the tub, a deflector plate spaced from the jet with its centre located substantially on the centre line of the tub, guide means for floatably retaining the deflection plate in position above the jet, the interior of the tub being unobstructed to provide a clear passageway for fluid from the jet to the deflector plate, the diameter of the jet opening being not more than half the diameter of the tub and the space between the jet and the walls of the tub being also unobstructed whereby when the tub is filled with fluid between the jet and the deflector plate the fluid entering the tub through the jet will induce a circulating movement of the fluid along said centre line to the deflector plate and outwardly to the walls of the tub and backwardly and inwardly to the jet, carrying with it any linen which has been placed in the tub, and means for circulating the fluid from the drainage opening to the jet and injecting it into the tub through the jet under pressure.

2. A machine for washing linen comprising an imperforate tub for holding linen and washing fluid, said tub having a bottom and side walls, a filling opening in the top thereof for inserting linen, a drainage opening adjacent the bottom thereof, a jet opening vertically into the tub adjacent the bottom thereof at substantially the centre line to inject washing fluid upwardly into the tub, a deflector plate having at least part of its undersurface concaved and spaced above the jet with its centre line located substantially on the vertical centre line of the tub, guide means for floatably retaining the deflector plate in position above the jet, the interior of the tub being unobstructed to provide a clear passageway for fluid from the jet to the deflector plate, the di-

ameter of the jet opening being not more than half the diameter of the tub and the space between the jet and the walls of the tub being also unobstructed whereby when the tub is filled with fluid between the jet and the deflector plate the fluid entering the tub through the jet will induce a circulating movement of the fluid along said centre line to the deflector plate and outwardly to the walls of the tub and backwardly and inwardly to the jet, carrying with it any linen which has been placed in the tub, and means for circulating the fluid from the drainage opening to the jet and injecting it into the tub through the jet under pressure.

3. A machine for washing linen as claimed in claim 2, including a closure for the filling opening, said guide means including a depending member on the closure and an upstanding member on the plate telescoping with the depending member.

4. A machine for washing linen as claimed in claim 2, including a closure for the filling opening, said guide means including a bellows secured to the closure and the plate.

5. A machine for washing linen as claimed in

claim 2, including a perforated screen extending around the jet over the drainage opening and above the bottom of the tub, said jet extending through said screen so that there may be substantially unimpeded injection of washing fluid.
